UNITED STATES PATENT OFFICE

112,300

DESIGN FOR A TEXTILE FABRIC

Curt E. Forstmann, Montclair, N. J.

Application November 17, 1937, Serial No. 72,961

Term of patent 14 years

To all whom it may concern:

Be it known that I, Curt E. Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design consists of alternate series of vertical rows of thickened yarns in combination with thin tightly twisted yarns, said thickened yarns giving the appearance of broken plaid blocks, as shown.

I claim:

The ornamental design for a textile fabric, as described and as shown.

CURT E. FORSTMANN.
